(Cl. D85—2)

To all whom it may concern:

Be it known that I, Harold O. Caddel, a citizen of the United States, residing at Richmond, in the county of Contra Costa, and State of California, have invented a new, original, and ornamental Design for a Combined Coaster, Ash Tray, and Cigarette Snuffer or Similar Article, of which the following is a specification, reference being had to the accompanying drawing, forming part thereof.

Fig. 1 is a top plan view of a combined coaster, ash tray, and cigarette snuffer or similar article, showing my new design.

Fig. 2 is a front elevation of Fig. 1, all four sides being alike.

Fig. 3 is a bottom plan view, and

Fig. 4 is a section taken on line 4—4 of Fig. 1.

I claim:

The ornamental design for a combined coaster, ash tray, and cigarette snuffer or similar article, as shown.

HAROLD O. CADDEL.
